UNITED STATES PATENT OFFICE

WALTER CHARLES TROUT, OF LUFKIN, TEXAS

DUSTPROOF CENTER IRON FOR WALKING BEAMS

Application filed September 4, 1928. Serial No. 303,840.

My invention relates to center irons for use upon Samson posts to support the walking beam. It is adapted for use particularly in oil field operations on standard drilling and pumping rigs.

The ordinary type of center iron is formed with a trunnion supported at each end in open bearings. The objection to this type of bearing is that it is exposed to dust and to the action of the weather and wears rapidly.

It is an object of my invention to provide a supporting bearing for the walking beam which shall have a wide support for the full width of the walking beam and to have this support fully enclosed and protected from dust and the weather.

It is also an object to provide an effective means for lubricating the bearing so that the moving parts of the bearing member will be running in oil at all times.

It is a further object to provide a center bearing for the walking beam of simple and strong construction having effective means for attaching it to the Samson post so that it may be adjusted to set the walking beam at the desired angle relative to the post.

In the drawing herewith I have illustrated a preferred embodiment of my invention, Fig. 1, being a central vertical section longitudinally of the bearing shaft. Fig. 2 is a top plan view of the bearing member partly in horizontal section. Fig. 3 is a central vertical section on the plane 3-3 of Fig. 1. Fig. 4 is an assembly view illustrating the position of the center bearing relative to the post and walking beam.

With particular reference to Fig. 4, it is to be noted that the center bearing, indicated at A is positioned upon the upper end of a Samson post 6 of ordinary construction and serves to support on its upper side a walking beam 7, also of ordinary construction. The walking beam is given a rocking motion upon the center bearing A through a crank shaft 8, crank arm 9 and pitman 10. The opposite end of the walking beam has a pump rod 11 secured thereto, said rod being reciprocated in the well in pumping. It is to be understood that the usual cable employed in drilling may

be secured in the place of the pump rod at the forward end of the beam.

The construction of the center iron is shown in Figs. 1 to 3 inclusive. There is a base plate 12 adapted to seat upon the upper end of the Samson post. Said base plate is formed with a central opening 13 therein to receive a bolt 14 by means of which it is secured centrally to the Samson post. At each end and at the sides are formed arcuate slots 15' to receive set screws or bolts clamping the same at each end adjustably to the post. The slots are formed on an arc about the center 14 allowing an adjustment of the plate upon the post to allow the swinging of the beam relative to the Samson post to a position properly aligned between the operating crank arm and the well.

The base plate is formed with supporting members 17 projecting upwardly from the base at each end and concaved longitudinally of the plate to receive the bearing 16 for the shaft 15 on the walking beam. Said bearing 16 is supported at each end upon said supports; and between the supports 17 the base plate is recessed at 18 to allow the passage of a sleeve 19 which will be later referred to. The stationary bearing 16 is held to the base by dowel pins 20, and I have shown two of these, one adjacent each end of the bearing. As will be seen particularly from Fig. 1, the bearing plate 16 is provided with a plurality of transverse grooves 22 which extend across the plate nearly to the upper edge thereof. From Fig. 3 it will be noted that there is a longitudinal channel 23 which serves to connect the grooves 22 at their upper edges longitudinally of the bearing.

An inner lining 24 for the bearing member is provided, this lining being preferably of babbitt, bronze or similar bearing material having a low co-efficient of friction. The dowel pins 20 extend through this lining member to hold the same rigidly in position. Small openings or channels 25 are extended through the lining member connecting the same with the grooves 22 so that lubricant can find easy access to the shaft. At each end of the shaft 15 I provide an upper bearing member 26 which surrounds the upper side

of the shaft and is bolted firmly in position by bolts 27. Within the bearing member thus provided is a bearing block 28 which fits along the upper side of the shaft and serves as a thrust member on the upper side of the said shaft. The block is secured in position by cap screws 29.

The walking beam is supported upon a plate 30 which extends transversely of the shaft 25 and is adapted to move with said shaft. It is fixed to said shaft by means of cap screws 31 which extend downwardly through the plate and into the upper side of the shaft. The upper portion of the plate 30 is extended inwardly along the upper side of the shaft and a piece of packing material 32 is fitted between the plate and the shaft, the shaft being recessed longitudinally at 33 to receive a lip 34 upon the packing.

The plate 30 has a sleeve 19 previously referred to, which is connected at its upper side with the body of the plate, as will be noted particularly from Fig. 3. This sleeve surrounds the shaft and the lower bearing to provide a housing therefor to protect the bearing from dust and dirt and also to form a container for the lubricant which might otherwise leak away from the bearing member. Between the ends of the base plate the sleeve 19 fits within the recess 18 in the base plate and its ends make a sliding contact with the plate and a packing material indicated at 35 is set into the ends of the sleeve to bear against the ends of the recess 18, making a fluid-tight fit therewith. This ring of packing entirely encloses the shaft and makes a fluid-seal to prevent the loss of lubricant, and prevents the entrance of dust.

At each end of the shaft 15 and the bearing member a plate 36 closes the end of the bearing housing provided by the plates as described and a lubricant cup 37 is formed on said plate 36 into which lubricant may be poured to supply the bearings with lubricant in the manner previously noted. The level of the lubricant is preferably about the center of the shaft so that the lubricant will flow along the channel 23 to supply each of the grooves 22 with a full quota of lubricant. A cap plate 38 is formed upon the upper end of the lubricant chamber to close the same when in use. I may also provide a screw plug 39 at the lower end of the chamber to allow cleaning of the lubricant chamber when desired.

The plate 30 upon which the walking beam is supported has a plurality of openings 40 therein by means of which the walking beam may be secured firmly to the plate.

In the operation of the device the weight of the walking beam will be supported upon the plate 30 centrally between the ends of the shaft 15 and the weight of the walking beam will rest upon the bearings as described. It will be noted that the ends of the shaft are

entirely closed by the upper and lower bearing plates, while the central portion of the shaft is surrounded by the sleeve 19 secured to the plate 30 upon which the beam is secured. Thus when the beam is rocked with the shaft 15 upon the bearings the sleeve 19 will oscillate with the shaft and the beam. The supporting plate 12 and the bearing members will be held stationary on the upper end of the Samson post.

When the device is operated it will be supplied plentifully with oil or other lubricant so that the level of the lubricant will be high enough to fill the connecting channel 23 between the grooves 22.

If the walking beam is not in accurate alignment between the operating shaft and the pump rod such alignment may be secured by adjusting the base plate 12 upon the Samson post through set screws within the slots 85, as previously noted.

This device has the advantage of obtaining a full support for the walking beam for the entire length of the shaft. Instead of being supported simply at its ends the bearing shaft 15 is supported throughout its entire length. This fact, together with the manner in which the shaft is enclosed and lubricated, unite in forming a substantial and dustproof bearing which is capable of proper lubrication and will be enabled to endure for long periods of time.

What I claim is:

1. A center iron comprising a base plate, having a recessed center portion and bearing supports at each end, a bearing plate fixed on said base plate, a shaft mounted to oscillate on said bearing plate, a beam plate secured to said shaft, and means movable with said beam plate surrounding said shaft and said bearing plate to prevent entrance of dust to said bearing.

2. A center iron comprising a base plate having its upper face recessed between its ends, a bearing plate supported at its ends on said base plate, a shaft mounted to bear for its full length on said bearing plate, and a beam plate fixed to said shaft and carrying a dustproof sleeve to surround said bearing plate and shaft.

3. A center iron comprising a base plate having its upper face recessed between its ends, a bearing plate supported at its ends on said base plate, a shaft mounted to bear for its full length on said bearing plate, means to allow said base plate to be moved rotatively to adjust the position of the beam, and a beam plate fixed to said shaft and carrying a sleeve to co-operate with the said base plate to completely enclose said shaft.

4. A center iron comprising a base plate having its upper face recessed between its ends, a bearing plate supported at its ends on said base plate, a shaft mounted to bear for its full length on said bearing plate, a beam

plate fixed to said shaft, and a sleeve fixed on said beam plate and surrounding said shaft and bearing plate.

5. A center iron comprising a base plate having its upper face recessed between its ends, a bearing plate supported at its ends on said base plate, a shaft mounted to bear for its full length on said bearing plate, a beam plate fixed to said shaft, and a sleeve fixed on said beam plate and surrounding said shaft and bearing plate, said sleeve making a fluid tight fit with said base plate and bearing plate, and means to lubricate said bearing.

15. 6. A center iron comprising a base plate, bearing supports at each end thereof, a bearing plate with a series of transverse grooves on said supports, a semi-cylindrical bearing liner on said bearing plate, there being openings in said bearing liner communicating with grooves in said bearing plate, means to supply lubricant to said grooves, a shaft in said liner, and a beam supporting plate on said shaft.

25. 7. A center iron comprising a base plate, bearing supports at each end thereof, a bearing plate with a series of transverse grooves on said supports, a semi-cylindrical bearing liner on said bearing plate, there being openings in said bearing liner communicating with grooves in said bearing plate, a lubricant cup at each end of said bearing plate adapted to supply lubricant to said bearing liner, a shaft in said liner, and a beam-supporting plate on said shaft.

35. 8. In a center iron, a base plate, bearing supports at each end thereof, a bearing plate with a series of transverse grooves fixed on said supports, a shaft mounted to oscillate in said bearing plate, a beam-supporting plate fixed to said shaft, and a sleeve on said beam supporting plate surrounding said bearing between said bearing supports.

45. 9. In a center iron, a base plate, bearing supports at each end thereof, a bearing plate with a series of transverse grooves fixed on said supports, a shaft mounted to oscillate in said bearing plate, a beam-supporting plate fixed to said shaft, and means mounted to oscillate with said shaft and enclose said bearing plate and shaft during the operation of the device.

55. 10. In a center bearing, a base plate, end supports thereon, a bearing plate on said supports, a shaft supported in said bearing plate, a beam plate fixed on said shaft for oscillation in said bearing, and a sleeve on said beam plate and surrounding said bearing plate and shaft between said supports, and making a fluid tight seal with said supports for the purpose described.

65. 11. A dustproof center iron, comprising in combination a base plate, a lower bearing plate supported thereby, a shaft supported on said plate for its full length, upper bearing

members retaining said shaft on said lower bearing plate, a beam supporting plate attached to said shaft, and a circular sleeve carried by said beam plate of such diameter to receive said shaft and said lower bearing plate therein, and to cooperate with said base plate and said upper bearing members to enclose said shaft and said lower bearing plate.

70. 12. A dustproof center iron comprising a base plate, lower and upper bearing plates, a beam supporting plate, and a sleeve carried thereby, a packing between said upper bearing plate and said base plate and sleeve, whereby the shaft and bearing plate are enclosed.

75. 13. A dustproof center iron comprising a base plate, lower and upper bearing plates, a beam supporting plate, and a sleeve carried thereby, a packing between said upper bearing plate and said base plate and sleeve, whereby the shaft and bearing plate are enclosed, and dustproof end plates to enclose the ends of said shaft.

80. 14. A dustproof center iron, comprising a base plate, a shaft, a lower bearing plate, adapted to support said shaft over its entire length, bearing blocks, upper bearing plates retaining said shaft and said block upon said lower plate, a beam supporting member, and means including a housing disposed around 90 and plates at the ends of said shaft to completely enclose the same and to prevent the entrance of dust.

95. 15. A dustproof center iron comprising a base plate, lower and upper bearing plates, a beam supporting plate, and a sleeve carried thereby, a packing between said upper bearing plate and said beam plate and sleeve, whereby the shaft and lower bearing plate are enclosed, dustproof end plates to enclose 100 the ends of said shaft, and an oil cup and cover therefor carried by said end plates.

105. In testimony whereof I hereunto affix my signature this 28th day of August, A. D. 1928.

WALTER CHARLES TROUT.
